UNITED STATES PATENT OFFICE.

FRIEDERICH MÜLLER, OF HARTFORD, CONNECTICUT, ASSIGNOR TO PRATT & WHITNEY COMPANY, OF HARTFORD, CONNECTICUT, A CORPORATION OF NEW JERSEY.

MAGAZINE MECHANISM.

1,252,929.

Specification of Letters Patent. Patented Jan. 8, 1918.

Original application filed January 3, 1910, Serial No. 536,106. Divided and this application filed June 13, 1910, Serial No. 566,468. Renewed October 23, 1917. Serial No. 198,180.

To all whom it may concern:

Be it known that I, FRIEDERICH MÜLLER, a citizen of the United States, residing at Hartford, in the county of Hartford and 5 State of Connecticut, have invented certain new and useful Improvements in Magazine Mechanism, of which the following is a specification.

This invention relates to magazine mechanism which can be used in divers ways, although it is of peculiar importance when employed in combination with or as part of a lathe such as shown in my copending application filed January 3, 1910, Serial No. 15 536,106, of which this present case is a division.

One of the primary purposes of the invention is the provision of magazine mechanism including a magazine and a stock or 20 blank transferring device which have effective means for accurately and precisely obtaining various adjustments so as to adapt it to the stock being operated upon in the machine with which the magazine mechanism is associated. There are other features of novelty and advantage which with the foregoing will be set forth at length in the following description wherein I will outline in detail that form of embodiment of the 25 invention which I have selected for illustration in the drawings accompanying and forming part of the present specification.

I do not restrict myself to the disclosure made by said drawings and description, 30 which is provided to enable those skilled in the art to practice the invention. I may depart radically from said showing within the scope of my invention as expressed in the claims succeeding said description.

40 Referring to said drawings:

Figure 1 is a plan view partially in section of magazine mechanism involving my invention.

Fig. 2 is a sectional view on the line 2—2 45 of Fig. 1.

Fig. 3 is a front elevation of one side of the magazine.

Figs. 4, 5 and 6 are detail views in isometric projection.

50 Like characters refer to like parts throughout the several figures.

The magazine mechanism embraces in its organization a magazine such as that denoted in a general way by 5, and a trans-

ferring device as that denoted in a general 55 way by 6, the magazine being generally stationary and the transferring device serving to carry or conduct a blank or equivalent device from the magazine to a desired point, for instance, between the centers of a lathe, 60 the said stock transferring device being in the present case reciprocatory.

The different parts of the magazine 5 are sustained by suitable framing which may, as shown, consist of two standards or uprights as 7 which are normally stationary and which are connected in some suitable manner with the framing of the machine in connection with which the magazine is employed. As the two standards 7 are similar in construction, a detailed description of one will apply to the other. I have shown fitted against the inner flat surface of said standard 7 a plate as 10 and similarly fitted against said plate 10 is a substantially similar plate 11, said plates having longitudinally extending flanges or lips 13 and 14 at their forward sides which in the present case extend vertically in parallelism, the space between said flanges or lips constituting a run way or channel 15 to receive one end of the blanks which gravitate along the magazine, the other end of the blanks fitting a corresponding run way on the other side of said magazine. The flanges or lips 13 and 14 as will hereinafter appear, can be adjusted toward and from each other so as 70 accurately to adopt the run way to the size of the work. By referring to Fig. 1 it will be clear that the magazine is provided with 75 end walls which in the present construction are formed by the plates 10. These end walls coöperate with the side walls formed by the flanges 13 and 14 to form the respective 80 runways.

In order that the plates may be adjusted toward and from each other as before mentioned, I preferably provide means whereby they can be moved longitudinally. While I do not limit myself to any one means for 85 this purpose, that which will now be described is quite satisfactory.

The plates 10 and 11 are shown as having laterally extending lugs or ears 16 and 17 in superimposed relation, said lugs having 100 elongated slots each designated by 18, the elongation of said slots being from front to rear of the magazine. Each standard 7 is 105

provided at its upper end with an outward extending head or projection 8 which is adapted to receive an adjusting screw 9 which extends through the aforesaid slots 18. 5 I have shown pinned to the upper end of said screw 9 a knurled head 19, the lower end of which (acting as a shoulder) bears against the upper surface of the ear 17 while the lower ear 16 bears against a collar as 20 on the screw 9. I provide in effect that these two ears or lugs 16 and 17 be snugly fitted between the two shoulders or confining faces of the screw, and it will be obvious that when said screw is run into or 10 out of its seat, the two plates 10 and 11 are respectively lowered and raised in unison. The plates 10 and 11 are shown having slots 21 and 22 disposed transversely or at right angles to each other and through these 15 slots a bolt 23 is passed, said bolt being rigidly connected with the standards 7 and the nut 24 thereof being adapted to clamp said plates 10 and 11 in adjusted positions. When it becomes necessary to change the 20 width of the run way or channel 15, the nut 24 is first loosened after which the plates are raised and lowered as may be demanded and after the adjustment is secured the nut 24 is tightened. 25 Owing to the described construction, it will be apparent that when said plates 10 and 11 are raised, the walls or flanges 13 and 14 are caused to separate to widen the run way 15, while on the lowering of the plates, 30 the two walls will be caused to approach to narrow said run way, the slots 18 freely permitting lateral movement of the two plates 10 and 11 as they are raised and lowered. During the adjustment of the run way, the 35 center line thereof never varies; that is to say said center line is not moved forward or backward, although the size or the width of said run way is changed; this change however, is obtained by moving the said 40 walls of the run way 15 simultaneously toward or simultaneously away from each other or by giving to said walls the same amount of lateral movement. Then also it is apparent that the run way or channel at 45 one side of the magazine can be adjusted independently of the other. While the work shown in the magazine is assumed to be cylindrical in form and of uniform diameter throughout its length, the run ways in this 50 case are uniform in width. If the work were of different diameters at its ends, one run way would have to be larger than the other and in view of the independent adjustment of the run ways the magazine is adapted to 55 contain work which differs in size at its ends. It is, of course, not essential that the work be cylindrical in form; it might be square or polygonal in cross-section. 60 The laterally enlarged or widened base or 65 foot 25 of each standard 7 supports for slid-

ing movement a plate 26 constituting part of the stock transferring device 6, said plate traveling longitudinally. In the case of a lathe the movement of this plate will be transverse or crosswise of the bed thereof. 70 The base 27 of this plate is made practically in dove tail form and one side thereof bears against an angular face on the lower portion of the standard 7, while an angular face on the gib 28 bears against the opposite side of 75 said dove tail portion 27. The plate 26 and a complementary plate supported by the other standard comprise the body portion of the stock or blank transferring device 6, and the two plates connected by a rod as 29 which 80 extends through slots 30 in the two plates. To the said rod 29 are connected arms 31, only one of which is shown, which are oscillatory, being intermittently operated so as to impart a reciprocatory movement to the 85 stock transferring device, the latter on the forward movement thereof being adapted to transfer a blank from the magazine 5 to the desired place and on its back stroke returning for a new blank. The means for operating the stock transferring device forms no 90 part of the present invention for which reason it is not necessary for me to describe, or illustrate it. It will be remembered that I have been describing the standard 7 and 95 plate 26 supported thereby at one side of the magazine mechanism these being duplicated, as will be evident, at the opposite side of the said mechanism. I will now proceed further with the description of the plate 26 100 and its adjuncts.

Fitted against opposite sides of the plate 26 are plates 32 and 33 having oblique slots each designated by 34 to receive the bolt 35 rigidly supported by the intermediate plate 105 26 and having a nut 36 which constitutes a simple means for clamping the plates normally to each other. From this it will be evident that the plates 32 and 33 are adjustable and this adjustment is utilized in the 110 present case to vary the size of the blank or stock transferring receptacle 6. The central or intermediate plate 26 is shown supporting for oscillation two rockers each denoted by 37 which have substantial central, circular 115 bearing or fulcrum portions 38 fitted for rocking motion in circular seats in said intermediate plate 26, the latter being also slotted as shown at 39 in each case to permit of the swinging of said two levers or rockers 120 37 which it might be stated present a suitable equalizing means between the two adjustable plates 32 and 33. The rockers are shown provided at their centers with outwardly extending pins or studs 40 which extend through matched guide slots 41 in the two side plates 32 and 33, it being understood that each rocker has two of such pins or studs 40. The terminals or opposite ends of the rockers or levers 37 are forked, the 125 130

outer side plate 32 having pins 42 near its upper edge to fit the upper forks while the inner plate 33 has pins 43 near its lower edge to fit the two lower forks. It will be assumed that the outer plate 32 is thrust down, the nut 36 having been loosened to permit this action. On the downward motion of said outer plate it is moved forward and at the same time the inner plate 33 will be elevated and moved rearward, the degrees of movement of the two plates being identical owing to the presence of the interposed equalizing mechanism and this movement is what is utilized in the present case to regulate the size of the blank receiving pocket or aperture of the blank or stock transferring device 6. When the adjustment is obtained the nut 36 will be tightened. In the illustration given the pocket in the blank transferring device will be narrowed while if the operation be reversed, the opposite result will occur, as will hereinafter more particularly appear.

The inner plate 33 has a substantially right angular cut away portion or rabbet 44 at its front end which forms part of a pocket or aperture 45 for receiving the blank to be transferred said blank dropping from the runway 15 of the magazine. A detent or latch 46 of substantially right angular shape is pivoted at its approximately horizontal branch as at 47 to the reduced forward portion of said inner plate 33, the pocket or aperture 45 in which the blank is received has a bottom and two sides, the bottom consisting of the bottom of the cut away portion or rabbet 44, the inner wall being the front edge of the outer plate 32 and the forward wall being the inner side of the vertical branch of the detent or latch 46. This latch is normally held in operative relation by a spring 48 coiled about the pivot 47, said latch at such time bearing against the stop pin 49 on the inner plate 33.

The blank transferring device 6 when in blank receiving position has the two pockets or apertures 45 in vertical alignment with the respective run ways 15 so that there will be nothing to prevent the gravitation of the lowermost blank in the magazine into the apertures or pockets. Clearly when the transferring device is in the position shown the bottom of the aperture forms a bottom wall for the runway. It will be assumed that a blank is in the two seats or apertures of said blank transferring device and that the latter has just commenced to advance to transfer said blank. When the transferring device is moved forward the outer plates 32 will be under the lower open ends of the two run ways to stop the descent of the blanks. When the blank transferred has been positioned, said blank transferring device will be drawn back and during this motion, the latches 46 will automatically re-

cede or be tripped and thereby freed from the blank. In the case of a lathe, the centered blank which, of course, is clamped in position between the centers is utilized to trip the two latches simultaneously. The instant that the latches are freed from the blank thus centered, they are at once returned to their original positions by the springs 48. It will be understood that the blank receiving aperture 45 at one side of the transferring device can be adjusted independently of the other. When the transferring device is in its retracted position the latches 46 will be supported against lugs 50 on the gibs 28 so that the weight of the pile or stack of blanks is thereby taken from said latches. Inasmuch as the upper edge of the plate 32 engages the bottom edge of the plate 11, either of these plates can be adjusted first and then used as a gage for the adjustment of the other. In this way it is possible for the operator to adjust the aperture in the transferring device to the proper size and then correspondingly adjust the runway; or it is possible for him to first adjust the runway to the proper size and then correspondingly adjust the aperture. Either device serves as a gage for the adjustment of the other and in either case the center of the aperture, when in blank receiving position, is coincident with the central plane of the runway. Preferably the aperture is adjusted first by properly moving the plates 32 and 33 and then the runway is adjusted by moving the plates 10 and 11 downward until the plate 11 engages the plate 32.

It will be observed that there is a definite relation between the vertical adjustment of the plate 11 and the vertical adjustment of the bottom wall of the aperture. Inasmuch as the plate 11 is adjusted vertically to the same extent that it is adjusted horizontally, it therefore follows that the vertical adjustment of the bottom of the aperture is also the same in extent as the horizontal adjustment of the plate. Thus the bottom of the aperture, which in effect forms the bottom of the runway, is moved to the same extent as the side walls of the runway, thus maintaining the axis of a fitting blank in fixed position.

This vertical adjustment of the bottom of the aperture also serves to maintain the axis of the fitting blank in a predetermined location when the transferring device is in its outer or blank supplying position. The adjustment of the device for blanks of different sizes in no way affects the position of the axis.

What I claim is:

1. A magazine comprising side walls forming the walls of a runway, means for moving them toward and away from a given line, and equalizing means so connecting

- them that they are moved to the same extent relative to such line.
2. A magazine comprising side walls forming the walls of a runway, means for moving them toward and away from a given line, equalizing means so connecting them that they are moved to the same extent relative to the line, and a locking device for securing them in their adjusted position.
- 10 3. A magazine comprising in combination an end wall and two parallel side plates forming a runway for blanks, and means for adjusting the plates toward or from each other along lines parallel with the end wall while holding them in parallelism with each other and for maintaining them equidistant from a fixed center line during such adjustment.
- 15 4. A magazine comprising in combination two spaced end walls and two pairs of parallel side plates, the plates of each pair cooperating with one end wall to form a runway for blanks, and means for adjusting the plates of each pair toward or from each other along lines parallel with the corresponding end wall while holding them in parallelism with each other and for maintaining them equidistant from a fixed center line during such adjustment.
- 20 5. A magazine provided with two plates having means forming collectively a blank runway, means for moving the plates up and down in unison, and means for causing uniform opposite lateral movements of the plates on their respective up and down movements.
- 25 6. A magazine comprising plates having flanges forming collectively a runway and also having slots disposed substantially at right angles to each other, a relatively fixed stud to extend through the slots, and means for moving the plates together in the direction of said flanges.
- 30 7. A magazine comprising two plates having slots disposed at substantially right angles to each other, laterally extending lugs on the plates having elongated holes, a screw extending through the holes having shoulders between which the lugs are closely fitted whereby the screw is adapted to raise and lower the plates together, and a relatively fixed stud for extending through the slots.
- 35 8. A magazine comprising in combination two parallel side plates forming a runway for blanks, a bottom wall at the lower end of the runway, means for adjusting the plates toward or from each other while holding them in parallelism and for maintaining them equidistant from a fixed center line during such adjustment, and means dependent on the adjustment of the side plates whereby the bottom wall may be adjusted to exactly the same extent longitudinally of the runway.
9. A magazine comprising in combination two parallel side plates forming a runway for blanks, a bottom wall at the lower end of the runway, means for adjusting the plates toward or from each other and for maintaining them equidistant from a fixed center line during such adjustment, the said means also serving to hold the plates in parallelism and to simultaneously adjust them longitudinally, and means dependent on the longitudinal adjustment of one of the plates whereby the bottom wall may be adjusted longitudinally of the runway.
10. In a magazine mechanism, the combination of adjustable members collectively providing means for contacting the blank at three different points, and means whereby a constant center is automatically maintained when said members are adjusted to receive blanks of different transverse dimensions.
11. A blank-transferring device comprising members having jointly an aperture provided with a bottom and sides and movable to vary both the width and depth of the aperture.
12. A blank-transferring device comprising members having jointly an aperture provided with a bottom and sides and movable to vary both the width and depth of the aperture, and equalizing means between the members for causing uniform movements of the sides and bottom.
13. In a magazine mechanism, in combination, a blank-transferring device having a receptacle for the blank, and means for moving the side walls of the receptacle and simultaneously increasing its depth so that the bottom and the side walls respectively are substantially equidistant from the center line of the receptacle.
14. In a device of the character described, in combination, a blank-transferring device having a limited path of travel and comprising two members relatively adjustable in the direction of the path of travel, the members collectively providing means for contacting the blank at three different points.
15. In a device of the character described, in combination, a blank-transferring device having a limited path of travel and comprising two members relatively adjustable in the direction of the path of travel, the members collectively providing means for contacting the blank at three different points, a portion of the said means being spring pressed into contacting position and yieldable to permit discharge of the blank.
16. In a device of the character described, in combination, a blank-transferring device having a limited path of travel and comprising two members relatively adjustable in the direction of the path of travel, the members collectively providing means for con-

tacting the blank at three different points, and means whereby a constant center is automatically maintained when said members are adjusted to receive blanks of different transverse dimensions.

5 17. A magazine provided with a blank runway, a blank-transferring device having an aperture to receive a blank from the runway, and mechanism for positioning the 10 sides of the runway and of the aperture at equal distances from the center lines thereof.

15 18. A magazine comprising two separate runways, means for independently adjusting the size of the runways, a blank-transferring device having apertures to register respectively with the runways, and means for adjusting the sizes of the apertures to correspond respectively with the sizes of the runways.

20 19. A magazine having a runway, and a blank-transferring device having an aperture to register with the runway, the magazine and the transferring device both being adjustable and one of them constituting a 25 gage for the adjustment of the other, whereby the runway and the aperture may be of the same size.

20 20. A magazine having a runway, and a blank-transferring device having an aperture to register with the runway, the magazine and the transferring device both being adjustable and the magazine constituting a gage for the adjustment of the transferring device, whereby the runway and the 35 aperture may be of the same size.

21. In a device of the character described, in combination, a blank-transferring device having a limited path of travel, and means comprising a runway whereby a blank is supplied to the transferring device, the said runway being adjustable to coöperate with blanks of different transverse dimensions while automatically maintaining a constant relationship between the center line of the 40 runway and an end of the path of travel of the transferring device.

45 22. In a device of the character described,

in combination, a blank-transferring device having a limited path of travel and comprising means adjustable to receive blanks 50 of different transverse dimensions, and means comprising a runway whereby a blank is supplied to the transferring device, the said runway being adjustable to coöperate with blanks of different dimensions while 55 automatically maintaining a constant relationship between the center line of the runway and an end of the path of travel of the transferring device.

23. In a device of the character described, 60 in combination, a runway for a blank comprising a pair of side walls, means whereby the said walls may be adjusted toward and from each other while automatically maintaining a constant center line for the runway, a blank-transferring device having a limited path of travel and comprising walls forming a blank-receiving aperture, and means whereby the walls of the aperture may be adjusted to coöperate with blanks of 65 different transverse dimensions while automatically maintaining a constant relationship at the end of the path of travel of the said device between the axis of a fitting blank and the said fixed center line of the 70 runway.

24. In a device of the character described, in combination, a blank-transferring device having a limited path of travel and comprising an aperture adapted to receive 80 blanks, a runway whereby a blank is supplied to the aperture when the transferring device is in one position, a yieldable latch forming one wall of the aperture, and means for positively supporting the latch when the 85 transferring device is in position with the aperture in register with the runway.

In testimony whereof I affix my signature in presence of two witnesses.

FRIEDERICH MÜLLER.
